FIG. 7

FIG. 8

UNITED STATES PATENT OFFICE

FRANK M. STEINER, OF MINNEAPOLIS, MINNESOTA, ASSIGNOR TO STEINER SALES COMPANY, OF SALT LAKE CITY, UTAH, A CORPORATION OF UTAH

STOP MECHANISM FOR TOWEL CABINETS

Application filed March 22, 1929. Serial No. 349,117.

In towel cabinets of the so-called continuous type, wherein provision is made for feeding a continuous length of towel web, it is desirable to provide means for intermittently checking the feed of the towel when a suitable or predetermined length has been delivered and thereby prevent the feeding of an unnecessary length and the too rapid use of the clean towel.

Various devices have been provided for this purpose, many of them of complicated, expensive construction, some including springs, undesirable because of the danger of breakage with no provision to prevent intermittent operation of the locking lever and practically continuous revolution of the feed roll.

It has been found in stop mechanisms employing a stop lever adapted to be tripped by the user and returned to its normal locking position when the feed roll begins its revolution, that if the user depresses the lever a second time during the revolution of the roll, it will be ineffective to check the roll at the end of its revolution and the delivery of the towel may be practically continuous, and hence it is possible for a maliciously inclined person to obtain a length of towel wholly unnecessary for his needs with practically no interruption in the continuous operation of the feed roll. This objection not only causes a waste of the towel through the delivery of an unnecessary length, but adds materially to the cost of up-keep of the cabinet.

The object therefore of my present invention is to provide a simple, inexpensive stop mechanism which will insure the delivery of a predetermined length of towel each time the release lever is manipulated and will also compel a pause or rest in the movement of the feed roll with each revolution thereof.

A further object is to provide a stop mechanism which will insure a slight initial movement of the delivery feed roll when the locking lever is depressed by the user, thereby preventing the lever from being returned to its locking position immediately following its release.

Other objects of the invention will appear from the following detailed description.

The invention consists generally of various constructions and combinations, all as hereinafter described, and particularly pointed out in the claims.

In the accompanying drawing forming a part of this specification,

Figure 1 is a side elevation of a towel cabinet with my invention applied thereto, the position of the towel supply and the web of towel leading therefrom, being indicated by dotted lines;

Figure 2 is a horizontal sectional view through the bearings of the feed rolls and the stop mechanism;

Figure 3 is a vertical sectional view on the line 3—3 of Figure 1;

Figure 4 is a detail view showing the stop lever in its released position having been moved to that position by the finger of the user from the locking position shown in Figure 1;

Figure 5 illustrates how the movement of the stop lever to its release position imparts a slight initial movement to the feed roll to prevent the immediate return of the stop lever to its locking position;

Figure 6 shows the position of the high point of the cam just previous to its engagement with the stop lever to move it to its locking position;

Figure 7 illustrates the position of the stop lever after its engagement by the high point of the cam and its movement to its locking position; and

Figure 8 illustrates how the high surface of the cam remains in continuous contact with the edge of the stop lever and prevents any movement of the stop lever to its release position until just prior to the engagement of the cam with the stop lug on the lever.

In the drawing, 2 represents the casing of a towel cabinet made of any suitable material and adapted to stand upon the floor or be secured on the wall, as preferred. The front of this cabinet has an opening, not shown, through which access is had to the clean towel web 3 that is received from a supply 4 supported by suitable means such as a shelf 5 within the cabinet. The clean web is stretched from this supply up over a de-

- livery feed roll 6 and a similar roll 7 is provided adjacent the roll 6 with a suitable driving connection such as gears 8 between them to insure simultaneous movement. The towel web is formed in a loop within the cabinet and the loose end is carried up in the rear of the supply to a soiled towel take-up roll 9 that is mounted in suitable guides 10 and is adapted to rest by gravity upon the roughened surface of the roll 7, all as substantially shown and described in prior patents of this art.
- The gears 8 are preferably on the ends of the rolls within a recess 11 in the wall of the cabinet, a plate 12 removably secured to the cabinet wall permitting access to this recess and the gear of the roll 7 has a suitable gudgeon 13 suitably supported on the inner face of the plate 12, while the roll 6 is preferably provided with a cam 14 that is secured by suitable means such as screws 15 to the end of the roll through the gear and has a gudgeon 16 journaled on the plate 12 similar to the bearing of the roll 7. This cam 25 has a stop 17 formed in its peripheral edge forming an off-set at the point on the cam periphery where the high edge or surface 18 of the cam merges into the low side or surface 19. This cam is of suitable size and being rigidly secured to the end of the roll, revolves with it during the feeding operation of the towel. 21 represents a stop lever that is substantially in the form of a sickle and provided with a pivot 22 supported in a bearing 23 in the plate 12 and having a lock nut 24 by means of which the pivot may be tightened and a compression spring 25, inserted between the plate and the stop lever, put under tension so that the lever will be frictionally held in its adjusted positions. The lever has a lug 26 in position to engage the stop 17 and a horizontal finger piece 27 which projects outwardly as indicated in Figure 1, to a point where it can be conveniently grasped by the user of the cabinet. The opposite end of the lever has a surface 28 which is outwardly curved as shown in the detail figures and when the lever is moved to its release position, this surface will be 50 in the path of the high edge of the cam to return the stop lever to its locking position before the cam completes its revolution.
- When the lever is moved to its release position as indicated in Figure 4, the surface 28 will engage the edge of the cam at the point 20 on one side of a line through the axis of the cam and the pivot of the lever and the high part of the cam is so shaped that the latter part of the movement of the stop lever 60 to its release position will impart a slight rotary movement to the cam, and therefore when the lever is in its release position and the cam moved slightly as shown in Figure 5, it will not be possible for the stop lever 65 to be returned to its locking position until

the cam and roll are revolved. Thus a user having moved the stop lever to the release point with one hand, may release the lever entirely if he so desires and obtain a suitable length of towel by pull upon the towel web either with one or both hands. The stop lever remains in its release position until the cam passes the point shown in Figure 6 and the high surface 18 engages the surface 28 of the lever. At this point, the lever is positively returned to its locking position and this movement slowly continues until the cam has nearly completed its revolution and is in the position shown in Figure 8. At this point the stop on the cam and the lug on the lever are nearly in engagement, and while at this point it would be possible for the user to again trip the lever, the time is so short before the stop engages the lug, that it is practically impossible for the lever to be manipulated a second time and another length of towel obtained before the cam and the feed roll have come to a complete stop, and the movement of the feed mechanism entirely arrested.

This is an important feature in a towel cabinet. It has been learned through dealings with the public in the marketing of clean toweling by the use of cabinets, that boys or maliciously inclined persons will often trip a stop mechanism, and if they find that by moving the lever to its release position a second time during the revolution of the roll, that a practically continuous feed of the towel can be obtained, they will adopt this practice merely for amusement and soon the supply of towel will be exhausted, most of the web being practically clean and unused.

The form of stop mechanism herein described, I have found from actual tests, prevents this manipulation of the feed device and by positively insuring the complete stoppage of the feed roll, once with every revolution discourages the unnecessary feed of the towel and effects a considerable economy in the operation and up-keep of the cabinet. Furthermore, the cam being rigidly secured to the end of the feed roll, revolves always as a part of the roll and prevents any possible defeat of the effective operation of the device through loose connections or failure of the stop mechanism to operate in conjunction with the towel delivery.

In various ways the details of construction herein shown and described, may be modified and still be within the scope of my invention.

I claim as my invention:

1. A towel cabinet comprising a casing, a feed roll for the clean towel therein, a cam operated by the revolution of said roll, said cam having a peripheral off-set forming a stop, a locking lever having a finger piece and a lug in the path of said stop when said lever is in its locking position, said lever also

having a cam surface to engage the high part of said cam after its initial movement and impart a slight initial rotary movement thereto when said lever is moved to its release position.

2. A towel cabinet comprising a casing, a feed roll for the clean towel therein, a cam operated by the revolution of said roll, said cam having a radially extending peripheral off-set forming a stop, a tilting locking lever having a finger piece and a lug in the path of said stop when said lever is in its locking position, said cam having a part to engage said lever and positively return it to its locking position and also having a camming surface to hold said lever in such position until said cam has nearly completed its stroke.

3. A towel cabinet and a feed roll for the clean towel therein, a cam secured to one end of said roll and having a peripheral off-set in the plane of the cam forming a stop, a lever pivoted at a point intermediate to its ends and having a finger piece and a lug adjacent thereto in the path of said stop, said lever having a curved end portion to engage and ride on the periphery of said cam when said lever is moved to its release position, said cam having a peripheral edge to engage the end of said lever and positively return it to its locking position, the periphery of said cam being adapted to remain in contact with said lever and prevent its movement to its release position until said cam has nearly completed its revolution.

4. A towel cabinet comprising a casing, a feed roll within the casing, a cam plate secured to the end of the feed roll and having a radial lock offset, said plate having on its surface a circumferential cam terminating at said radial offset, a tilting locking lever projecting through the casing, with its inner end embracing said cam and itself cam shaped on its adjacent edge, the cam shaped portion terminating in a lug to cooperate with said cam, the arrangement being such that an operation of the lever to disengage its lug from the cam offset will cause the cam portion of the lever to move the offset on the cam slightly beyond its locking position.

5. A towel cabinet comprising a casing, a feed roll therein, a cam on the feed roll having a radial locking offset, a lever pivoted in the casing with one end projecting outside the casing and having a cam surface inside the casing cooperating with said cam, a lug on the lever cooperating with said offset for locking said cam, the surface of the cam being adapted to cooperate with the inner end of the lever to force the lever to locking position and hold it in its locking position until the cam has nearly completed its rotation.

In witness whereof, I have hereunto set my hand this 18th day of March, 1929.

FRANK M. STEINER.
